United States Patent Office

Des. 204,634
Patented May 3, 1966

204,634

STUD DRIVER

William D. Chase, Stratford, and Charles J. De Caro, Orange, Conn., assignors to United Shoe Machinery Corporation, Flemington, N.J., a corporation of New Jersey

Filed Apr. 16, 1965, Ser. No. 84,815

Term of patent 14 years

(Cl. D54—10)

FIG. 1 is a perspective view of a stud driver embodying my new design;

FIG. 2 is a view in side elevation thereof;

FIG. 3 is a view of the device of FIG. 2 as seen from the bottom;

FIG. 4 is a view of the device of FIG. 3 as seen from the right end; and

FIG. 5 is a view of the device of FIG. 3 as seen from the left end.

We claim:

The ornamental design for a stud driver, substantially as shown.
